MACHINES FOR FASTENING STRIPS TO OTHER WORK

Edward Quinn, Saugus, Mass., and Wilbur W. Witt, Brewerton, N.Y., assignors to United Shoe Machinery Corporation, Flemington, N.J., a corporation of New Jersey

Filed June 19, 1957, Ser. No. 666,622

10 Claims. (Cl. 112—47)

This invention relates to improvements in slip-lasted shoe fastening and assembling machines similar to that disclosed in an application for United States Letters Patent Serial No. 621,796, filed November 13, 1956, in the name of Edward Quinn, one of the present inventors.

The machine of the prior application above identified is intended to operate upon slip-lasted shoe parts, including uppers, sock linings, and platform covers or wrapper strips, the latter of which are advanced toward the point of fastening operations in such a way that they are compressed lengthwise at the fastening point to facilitate the proper formation of the parts and the execution of further steps in shoe construction to be performed after the fastening operations have been completed.

It has been found that the wrapper strip advancing member of the above identified patent application requires relatively complex supporting structure and actuating mechanism. Such structure and mechanism require expert attention in the way of adjustment and maintenance, so that an obstacle is presented whenever an inexperienced operator attempts to utilize the machine.

One object of the present invention is to simplify the construction and improve the mode of operation of a slip-lasted shoe sewing or other fastening machine of the type referred to, by the provision of a wrapper strip advancing and lengthwise compressing member, the actuating mechanism for which is relatively simple and of light-weight design operated by directly acting and readily adjustable mechanism capable of being maintained in operating condition through a wide range of working conditions without the exercise of unusual or expert competence. Accordingly, a feature of the invention fulfilling this object resides in the provision of a fastening machine having a conventional work feed dog, a work-feeding presser foot acting toward and from the feed dog to clamp the work against the feed dog about an area surrounding the point of fastening operations and a wrapper strip advancing member separate from the feed dog acting on the strip only to move it toward the point of fastening operations, in which machine the mechanism for actuating the strip advancing member includes a set of connections having a simple direct relationship with the movements of the feed dog. As illustrated, the feed dog connections comprise a link pivoted to the feed dog, a slotted arm connected to the link, and a stud carried by the machine frame entering the slot in the arm to cause an advancing movement to be imparted to the strip by the advancing member simultaneously with the feeding action of the work as a whole by the presser foot and feed dog. Preferably, the movement of the strip advancing member does not exactly coincide, in point of time, with that of the feed dog, so that the work feeding portion of the feed dog movements is partially completed before the strip-advancing member starts to act. With such mechanism it is convenient to impart an overfeeding and compressing movement to the advancing member directly through the connections with

2

the feed dog, increasing the overfeeding movement within the remaining portion of feed dog operation to exceed the total feed of the work.

These and other features of the invention, as hereinabove described and claimed, will more readily be understood from the following detailed description taken in connection with the accompanying drawings, in which:

Fig. 1 is a view in left side elevation and partially in section of portions of a slip-lasted shoe sewing machine embodying the features of the present invention;

Fig. 2 is a view in front elevation on an enlarged scale of the parts surrounding the sewing point in the machine illustrated in Fig. 1, certain cover parts having been broken away to show the underlying construction;

Fig. 3 is a diagrammatic view partly broken away and in section on a further enlarged scale and in left side elevation of a strip advancing member and its actuating mechanism in the machine;

Fig. 4 is a detail perspective view with the parts of the strip advancing mechanism in separated relation showing a pivot connection between the work feed dog and a strip-advancing member;

Fig. 5 is a sectional detail view in left side elevation of some of the work clamping and other devices in the machine, illustrating the position of a wrapper strip and the other part of a slip-lasted shoe while the strip advancing member is disengaged from the wrapper strip at the beginning of a seam;

Fig. 6 is a similar view of the same parts, illustrating another position of the advancing member at the end of the first strip feeding movement before the first stitch of a seam has been inserted; and

Fig. 7 is a similar view of the same parts, illustrating the position of the advancing member after being disengaged from the wrapper strip after the first complete stitch has been inserted and the work has been fed.

The machine in the drawings is a straight eye-pointed needle lock stitch sewing machine, similar to that disclosed in United States Letters Patent No. 2,742,005, granted April 17, 1956, upon application of one of the present inventors. The machine has a main sewing head frame 2 within which is mounted a main sewing shaft 3, and a vertical reciprocating needle bar 4 at the lower end of which is clamped an eye-pointed needle 6. Co-operating with the needle to form lock stitches is a shuttle 8 (see Fig. 2) mounted in a supporting bracket 10 carried by a flat bed portion 12 (Fig. 1) of a main machine frame. Mounted on the flat bed portion 12, in side-by-side relation to the shuttle supporting bracket 10, is a bracket 14 forming with the bracket 10 a work-support or post of well-known construction. The work-support post has a work-engaging area of limited length and breadth to permit sewing of high arch shoes comprising a platform sole 16, shown in Fig. 2, attached to a sock lining 18, an upper 20 and a platform wrapper strip 22 (see Figs. 5 to 7, inclusive).

As in the machine of the Quinn prior application above identified and that of the patent just noted, the work is engaged by two alternately acting work clamps, one of which is driven from the sewing shaft 3 to feed the work and the other of which grips it while the feeding clamp is being back fed. In the machine of the prior application the feeding work clamp comprises a feed dog moving along the line of feed and a presser foot acting to clamp the work against the feed dog during feeding movements and to release the work during back feeding movements. For gripping the work during the back feeding movements of the feeding clamp a stationary work supporting table is provided and a nonfeeding presser foot clamps the work against the nonfeeding table. In the machine of the prior patent the work feeding clamp includes a two-part feed dog actuated with an orbital or four-motion

movement, not only in the line of feed but also toward and from the work to enable the work to become engaged with the work-supporting table during back feeding movement of the feeding clamp.

In the present illustrated machine the arrangement of the feeding and nonfeeding work clamps corresponds with that disclosed in the patent and advantage is taken of the orbital or four-motion movement of the feed dog to actuate the wrapper strip advancing member. In this way a directly acting set of connections is provided between the feed dog and the wrapper strip advancing member, the machine of the prior application being provided with a wrapper strip advancing member which is actuated by a rather complicated set of indirect connections with mechanism for imparting the work-feeding movement to the feeding clamp. Besides providing simple, directly acting connections for the wrapper strip advancing member in the machine of the present invention, the connections are more rigid, more durable, and more easily maintained in properly adjusted condition, especially where with the type of work being operated upon it is desirable to sew at relatively high speeds.

The illustrated arrangement for work clamping and feeding includes a nonfeeding work clamp, in which the leading edge of a hollow work-engaging abutment member 24 at the upper end of the supporting bracket 14 has pressed toward it a vertical portion of a nonfeeding presser foot 26. The feeding clamp includes a feed dog 28 entering at its perforated upper end within the abutment 24 and moving in an orbital path along the line of feed and toward and from the under surface of the work to lift it from engagement with the abutment 24 during work feed and to return it into engagement with the abutment during back feeding movement of the feeding clamp. Co-operating with the feed dog 28 is a presser foot 30 which also is given a similar four-motion movement to clamp the work and to move it along the line of feed, releasing it during back-feeding movement of the clamp. To assist in feeding the work the presser foot 30 and the needle bar 4 are guided for vertical movement in a feed carriage 31 movable in the frame 2 in the direction of work feed, the needle engaging the work during feed and being disengaged during back feed of the carriage.

In accordance with the present invention the directly acting connections between the sewing shaft driven feed dog 28 and the wrapper strip advancing member include a slotted horizontal link 32, best shown in Fig. 3. The rearward end of the link 32 is pivotally connected to the feed dog 28 and is supported by a fixed stud 34 passing through the slot which is formed in the central portion of the link. The forward end of the link is pivotally connected by a screw 36 to the lower part of a two-part arm 38-40, the parts being secured together in right angular relation by a screw 42. At the upper end of the arm part 40 of the advancing member is a wrapper strip advancing claw 44 secured by a clamp bolt 46 passing through a space between the forked portions of a shank for the claw and through a slot 48 formed at the upper end of the arm part 40, the upper end of the arm part 40 being offset to the left as shown in Fig. 2, so that the claw may engage a wrapper strip while the remainder of the arm part 38 avoids interference with the movement of the strip toward the sewing point.

To connect the link 32 with the feed dog 28, the feed dog has passing through it a screw 50 (see Fig. 4) and at diametrically opposite sides of the screw 50 is a pair of radial wings on a circular block 52 having a central threaded opening into which the screw 50 passes. The rearward end of the link 32 has an enlargement with a perforation fitting the outer surface of the block 52, a flange on the block preventing escape of the arm therefrom. To assist in securing the circular block 52 to the feed dog the block passes through an opening having

diametric recesses into which fit corresponding wings on the block.

To insure that the proper motion is imparted to the strip advancing claw 44, the lower end of the arm part 38 has a downwardly curved cam slot 53 fitting a fixed pin 54 projecting from a right-angle plate 56 secured to the frame of the work supporting post. The shape of the slot 53 in the arm 38 is such that during the four-motion movement of the feed dog 28 the center of the opening at its upper end moves in a four-motion orbit 58 indicated in Fig. 3, and the point of the advancing claw 44 moves in a four-motion orbit 60. As in the machine of the above-identified application, the wrapper strip 22 is led along the inclined surface of a ramp 62 disposed at an obtuse angle to the work-engaging surface of the work support in advance of the point of sewing operations and the needle 6. The effect of the curvature of the slot 53 is to change the shape of the orbit 58 into a flat-sided form for the orbit 60 wherein the claw 44 moves substantially parallel to the surface of the ramp 62 when in its position of closest approach thereto. If the bolt 46 is loosened and the claw is so located on the position of its orbit closest to the ramp 62 where it will engage a wrapper strip with a desired degree of penetration, then a uniform and reliable strip advancing movement will occur.

The four-motion movement of the feed dog 28 causes it to describe the orbit 58 as a result of the construction and arrangement of the feed dog and its driving connections with the sewing shaft. The feed dog is mounted on a lever 68 having a central slot in which is engaged a block 64 pivotally mounted on a fixed screw stud 66 threaded into the bracket 14 (Fig. 1). The lower end of the feed lever 68 has secured to it an actuating yoke 70, the yoke portion of which surrounds an eccentric 72 driven in unison with the main sewing shaft 3. A horizontal arm of the feed lever 68 is connected to a vertical arm of a lever 74 including a rock shaft 76, the other arm of the lever being actuated by mechanism timed to impart the proper feeding movements to the work and also to be driven from the sewing shaft 3.

Referring more particularly to Fig. 3, the feed dog engages and feeds the work during its movement from the position 1 of the orbit 58 through the position 2 and to the position 3, the advancing claw 44 acting to bulge and raise the work from the surface of the work support at the vertex of the angle between the ramp and the work support, in a manner to be described. During the time of this movement the total feed occurs between the positions 1 and 3. The presser foot 30 clamps the work against the feed dog during this feeding time. Also, during this feeding time the nonfeeding foot 26 is raised from the work.

To permit greater freedom of movement in the work in presenting it to the machine the connections between the feed dog and the strip advancing claw 44 cause the entire advancing movement to be imparted to the wrapper strip during the latter portion only of the work feeding time of the feed dog and the amount of this advancing movement is greater than the total movement imparted to the work by the feed dog. Thus, while the feed dog is at the position 1, the point of the advancing claw 44 is also in its position 1 disengaged from the wrapper strip. The advancing claw does not engage the wrapper strip ordinarily much before reaching the position 2 of its orbit 60, which position corresponds with the position 2 of the feed dog. At the position 2 the feed dog has reached a halfway point in its feeding movement. In order to provide a greater advancing movement of the wrapper strip toward the sewing point during the remaining portion of the feeding movement of the work the pivotal point of connection between the arm 38-40 and the link 32 is so selected, the stud 34 so located, and the slot 53 is so cut that the positions 2 and 3 of claw orbit 60 are at least twice the remaining movement of the feed

dog between positions 2 and 3 of the orbit 58. The movement of the advancing claw 44 between the positions 2 and 3 of orbit 60 also is substantially greater than the total amount of feeding movement of the feed dog between the positions 1 and 3 of the orbit 58. In this way an excess of wrapper strip is advanced toward the sewing point of the machine to cause the strip together with the sock lining and upper to be bulged by the advancing member at the vertex of an angle formed between the ramp 62 and the upper work-engaging surface of the work support. As illustrated in Fig. 6, as soon as the non-feeding presser foot 26 engages the upper surface of the work the bulge in the strip is flattened on the work support (Fig. 7) between the advancing claw and the feed dog.

To assist in guiding the wrapper strip and to hold the bulged strip in line with the sewing point the machine is equipped with a wrapper strip edge guiding pilot connected to the work support post at the vertex of the angle formed by the ramp and the work-engaging surface of the work support. The pilot comprises rolls 78 and 80 of the same construction and mode of operation as disclosed in United States Letters Patent No. 2,722,182, granted November 1, 1955, upon a joint application of Edward Quinn, one of the present inventors and Napoleon S. Ferland. The pilot rolls 78 and 80 are of special advantage in guiding relatively thick cover strips as they approach the work support and advance beyond the ramp but the rolls may be eliminated when thin, flexible strips are being sewn.

The nature and scope of the invention having been indicated and a particular embodiment having been described, what is claimed is:

1. A machine for manufacturing slip-lasted shoes having a main shaft, devices actuated by the main shaft for feeding and fastening one edge of a wrapper strip to other shoe parts, said devices including a work feed dog, a first presser foot acting toward and from the work feed dog to clamp the work parts about the point of fastening operations, a strip-advancing member separate from the feed dog for moving the strip toward the point of fastening operations, a work support and a second presser foot acting toward and from the work support to clamp the work between the first presser foot and the strip-advancing member, in combination with means comprising mechanism driven from the main shaft for actuating the strip-advancing member, including a link connected to the feed dog, an arm connected to the link, to one end of which arm the strip-advancing member is secured and at another end of which is a cam slot and a fixed pin on the machine frame engaging the cam slot to cause a strip advancing movement to be imparted to the advancing member while the first presser foot is clamping the work against the feed dog and while the second presser foot is raised from the work.

2. A machine for manufacturing slip-lasted shoes having a main sewing shaft, stitch-forming devices for feeding and sewing one edge of a wrapper strip to other shoe parts, said devices including a straight eye-pointed needle actuated by the main sewing shaft, a work feed dog, a first presser foot acting toward and from the work feed dog to clamp the work parts about the point of sewing operations, a strip-advancing member separate from the feed dog for moving the strip toward the point of sewing operations, a work support and a second presser foot acting toward and from the work support to clamp the work between the first presser foot and the strip-advancing member, in combination with means comprising mechanism driven from the main shaft for actuating the strip-advancing member, including a link connected to the feed dog, an arm connected to the link, to one end of which arm the strip-advancing member is secured and at another end of which is a cam slot, and a fixed pin on the machine frame engaging the cam slot to cause

a strip advancing movement to be imparted to the advancing member while the first presser foot is clamping the work against the feed dog and while the second presser foot is raised from the work.

- 5 3. A machine for manufacturing slip-lasted shoes, said machine having a main shaft, stitch-forming and work-feeding devices actuated by the main shaft for attaching one end of a wrapper strip to other work parts, said devices including a work feed dog acting through an orbit to engage, feed and disengage the work and to back feed while disengaged from the work, and a strip-advancing member separate from the feed dog acting on the strip only in advance of the feed dog, in combination with means comprising mechanism for actuating the strip-advancing member, including a link pivotally connected at one end to the feed dog, a sliding support for the midportion of the link, an arm connected to said link, to one end of which arm the strip-advancing member is secured and at another end of which arm is a cam slot, and means 10 including a pin carried by the machine frame and arranged to guide the advancing member through engagement with the slot in the arm, successively to engage, feed and disengage the strip.
- 15 4. A machine for manufacturing slip-lasted shoes, said machine having a main shaft, stitch-forming and work-feeding devices actuated by the main shaft for attaching one end of a wrapper strip to other work parts, said devices including a work feed dog acting through an orbit to engage, feed and disengage the work and to back feed while disengaged from the work, and a strip-advancing member separate from the feed dog acting on the strip only in advance of the feed dog, in combination with means comprising mechanism for actuating the strip-advancing member, including a link pivotally connected at one end to the feed dog, a sliding support for the midportion of the link, an arm connected to said link, to one end of which arm the strip-advancing member is secured and at another end of which arm is a cam slot, and means 20 including a pin carried by the machine frame and arranged to guide the advancing member through engagement with the slot in the arm, successively to engage, feed and disengage the strip.
- 25 5. A machine for manufacturing slip-lasted shoes, said machine having a main shaft, stitch-forming and work-feeding devices actuated by the main shaft for attaching one end of a wrapper strip to other work parts, said devices including a work feed dog acting through an orbit to engage, feed and disengage the work and to back feed while disengaged from the work, and a strip-advancing member separate from the feed dog acting on the strip only in advance of the feed dog, in combination with means comprising mechanism for actuating the strip-advancing member, including a link pivotally connected at one end to the feed dog, a sliding support for the midportion of the link, an arm connected to said link, to one end of which arm the strip-advancing member is secured and at another end of which arm is a cam slot, and means 30 including a pin carried by the machine frame and arranged to guide the advancing member through engagement with the slot in the arm, successively to engage, feed and disengage the strip.
- 35 6. A machine for manufacturing slip-lasted shoes, said machine having a main shaft, stitch-forming and work-feeding devices actuated by the main shaft for attaching one end of a wrapper strip to other work parts, said devices including a work feed dog acting through an orbit to engage, feed and disengage the work and to back feed while disengaged from the work, and a strip-advancing member separate from the feed dog acting on the strip only in advance of the feed dog, in combination with means comprising mechanism for actuating the strip-advancing member, including a link pivotally connected at one end to the feed dog, a sliding support for the midportion of the link, an arm connected to said link, to one end of which arm the strip-advancing member is secured and at another end of which arm is a cam slot, and means 40 including a pin carried by the machine frame and arranged to guide the advancing member through engagement with the slot in the arm, successively to engage, feed and disengage the strip, said cam slot being cut in the arm with a downwardly curved shape to disengage the strip-advancing member from the strip at the end of the work-feeding portion of the feed dog path and to retain the advancing member out of engagement with the strip until the work-feeding portion of the feed dog path is partially completed.
- 45 7. A machine for manufacturing slip-lasted shoes, said machine having a main shaft, stitch-forming and work-feeding devices actuated by the main shaft for attaching one end of a wrapper strip to other work parts, said devices including a work feed dog acting through an orbit to engage, feed and disengage the work and to back feed while disengaged from the work, and a strip-advancing member separate from the feed dog acting on the strip only in advance of the feed dog, in combination with means comprising mechanism for actuating the strip-advancing member, including a link pivotally connected at one end to the feed dog, a sliding support for the midportion of the link, an arm connected to the link, to one end of which arm the strip-advancing member is secured and at another end of which arm is a cam slot, and a pin carried by the machine frame and arranged to guide the advancing member through engagement with the slot in the arm, successively to engage, feed and disengage the strip, the point of pivotal connection between the advancing member and the link being selected to cause the advancing member to impart its entire feeding movement to the strip during the time in which the feed dog engages the strip, the entire feeding movement imparted to the strip by the advancing member being greater than the total movement imparted to the work by the feed dog.
- 50 8. A machine for manufacturing slip-lasted shoes, said machine having a main shaft, stitch-forming and work-

feeding devices actuated by the main shaft for attaching one end of a wrapper strip to other work parts, said devices including a work feed dog acting through an orbit to engage, feed and disengage the work and to back feed while disengaged from the work, and a strip-advancing member separate from the feed dog acting on the strip only in advance of the feed dog, in combination with means comprising mechanism for actuating the strip-advancing member, including a link pivotally connected at one end to the feed dog, a sliding support for the midportion of the link, an arm connected to said link, to one end of which arm the strip-advancing member is secured and at another end of which is a cam slot, and a pin carried by the machine frame and arranged to guide the advancing member through engagement with the slot in the arm, successively to engage, feed and disengage the strip, said cam slot being cut in the arm with a downwardly curved shape to disengage the strip-advancing member from the strip at the end of the work-feeding portion of the feed dog path and to retain the advancing member out of engagement with the strip until the work feeding portion of the feed dog path is partially completed, and the point of pivotal connection between the advancing member and the link being selected to cause the advancing member to impart its entire advancing moment to the strip during the time in which the other work is fed, the entire movement imparted to the strip by the advancing member being greater than that imparted to the work by the feed dog.

7. A machine for manufacturing slip-lasted shoes, said machine having a main shaft, stitch-forming and work-feeding devices actuated by the main shaft for attaching one end of a wrapper strip to other work parts, said devices including a work feed dog acting through an orbit to engage, feed and disengage the work and to back feed while disengaged from the work, and a strip advancing member separate from the feed dog acting on the strip only in advance of the feed dog, in combination with means for actuating the strip-advancing member, including a link pivotally connected at one end to the feed dog, a sliding support for the midportion of the link, an arm connected to said link to one end of which arm the strip-advancing member is secured and at another end of which is a cam slot, a pin carried by the machine frame and arranged to guide the advancing member through engagement with the slot in the arm, successively to engage, feed and disengage the strip, said cam slot being cut in the arm with a downwardly curved shape to disengage the strip-advancing member from the strip at the end of the work-feeding portion of the feed dog path and to retain the advancing member out of engagement with the strip until the work feeding portion of the feed dog path is partially completed, and a second presser foot for flattening the strip on the work support between the advancing member and the feed dog.

8. A machine for manufacturing slip-lasted shoes having a main shaft, devices actuated by the main shaft for feeding and fastening one edge of a wrapper strip to other work parts, said devices including a work support, a work feed dog acting from beneath the work support, a presser foot acting toward and from the feed dog to clamp the work parts about the point of fastening operations, a strip guiding ramp disposed at an obtuse angle to the work-engaging surface of the work support and a strip-advancing member for moving the strip along the ramp toward the point of fastening operations at a greater rate than that imparted to the work by the feed dog, in combination with means comprising mechanism for actu-

ating the strip-advancing member, including a link connected to the feed dog, an arm connected to the link, to one end of which arm the strip-advancing member is secured and at another end of which is a cam slot, and a pin carried by the machine frame entering the slot for imparting a strip-advancing movement to the advancing member to cause the strip to be bulged by the advancing member at the vertex of the angle formed between the ramp and the work support.

- 5 5. 10. 9. A machine for manufacturing slip-lasted shoes having a main shaft, devices actuated by the main shaft for feeding and fastening one edge of a wrapper strip to other work parts, said devices including a work support, a work feed dog acting from beneath the work support, a presser foot acting toward and from the feed dog to clamp the work parts about the point of fastening operations, a strip-guiding ramp disposed at an obtuse angle to the work-engaging surface of the work support and a strip advancing member for moving the strip along the ramp toward the point of fastening operations at a greater rate than that imparted to the work by the feed dog, in combination with means comprising mechanism for actuating the strip-advancing member, including a link connected to the feed dog, an arm connected to the link, to one end of which arm the strip-advancing member is secured and at another end of which is a cam slot, a pin carried by the machine frame entering the slot for imparting a strip-advancing movement to the advancing member to cause the strip to be bulged by the advancing member at the vertex of the angle formed between the ramp and the work support.
